UNITED STATES PATENT OFFICE.

ALLAN R. MACPHERSON, OF TACOMA, WASHINGTON.

GAME APPARATUS.

1,226,551.

Specification of Letters Patent. Patented May 15, 1917.

Application filed December 22, 1916. Serial No. 138,482.

To all whom it may concern:

Be it known that I, ALLAN R. MACPHERSON, a citizen of the United States, residing at Tacoma, in the county of Pierce and State 5 of Washington, have invented new and useful Improvements in Game Apparatus, of which the following is a specification.

This invention relates to games, and provides a game of war embodying among other 10 features a game piece for each player indicative of a trench, and upon which is mounted toy men and a cannon, the object of each player being to knock the men of his opponent behind the trench by projectiles delivered from the cannon in order to win the 15 game, the men of course being pivotally mounted for this purpose.

The invention further aims to provide a game of the above mentioned character 20 which can be cheaply manufactured and sold, and one which will afford considerable pleasure and amusement to those who engage in playing the game.

The nature and advantages of the invention will be better understood when the following description is read in connection with the accompanying drawing, the invention residing in the construction, combination and arrangement of parts as claimed.

30 In the drawing forming part of this specification like numerals of reference indicate similar parts in the several views and wherein:—

Figure 1 shows a side elevation of two of 35 the branches in position for use.

Fig. 2 is an end elevation of one of the trenches.

Fig. 3 is a sectional view taken on line 3—3 of Fig. 2.

40 Fig. 4 is a fragmentary plan view of a portion of the cannon.

A game constructed in accordance with my invention embodies two identically constructed game pieces shown at A and B respectively, and each of which game pieces is indicative of a trench. As both of the game pieces are identical in construction a brief description of one will suffice for both.

The body portion 10 of the trench may be 50 constructed from any suitable material and vary in design, but as shown in this particular instance the trench consists of a substantially L-shaped member with a horizontal branch or portion 11 constituting a 55 base adapted to rest upon the floor or surface. Arranged behind the vertical branch

12 of the trench is a plurality of toy men 13 indicative of soldiers and each provided with a gun 14. The men are hidden from view behind the vertical branch 12 of the 60 trench except their heads, which project a slight distance above the vertical branch 12. Mounted in any suitable manner upon the trench for horizontal swinging movement, is a toy cannon 15 including a spring pressed 65 plunger 17 through the instrumentality of which projectiles such as rubber balls, paper wads or the like can be discharged from the cannon of one trench in the direction of the opponent's trench with a view of knocking 70 the men of the latter mentioned trench backward out of view, resembling the killing of men. It is of course to be understood that the toy men 13 are pivotally mounted as at 17 whereby they may fall backward in 75 the manner above stated when struck by a projectile. The cannon is preferably mounted at a point midway in the length of the trench, and by reason of the fact that it can be swung in an arc of a circle in a horizontal plane the proper range of the opponent's trench may be readily obtained.

In practice the trenches are arranged in the manner illustrated in Fig. 1 with each player arranged behind his respective 85 trench. The projectiles are then arranged within the barrel of the cannon with the plunger retracted, and upon release of the latter the projectile or projectiles are discharged in the direction of the opponent's 90 trench with a view of killing the men associated therewith, as defined hereinabove. The winner of the game is the player who first succeeds in disposing of the toy men of his opponent. A game of this character 95 affords great pleasure and amusement to those engaged in playing the game, especially young folks, while the game can be manufactured and sold at a comparatively small cost.

100 The invention is also susceptible for use as a toy, in which instance the cannon as a unit is separated from the base of the trench, and arranged in front of the latter at any suitable distance therefrom. The cannon is 105 then operated in the manner above described with a view of knocking the men backward behind the trench, and when used in this manner only one of the devices is necessary. The cannon can be removably mounted upon 110 the base 11 in any suitable manner, as for instance the support for the cannon proper

may be provided with a key-hole slot 18 for the reception of the headed stud or rivet 19 projecting above the base 11.

While it is believed that from the foregoing description the nature and advantages of the invention will be readily apparent I desire to have it understood that such changes in the construction and arrangement of parts may be resorted to when desired as fall within the scope of what is claimed.

What is claimed is:—

1. A game of the character described embodying a pair of identically constructed game pieces adapted to be disposed in spaced confronting relation, and each being indicative of a trench, a plurality of toy men individually pivoted behind said trench with their heads projecting above the latter, and a cannon mounted upon each trench and capable of horizontal swinging movement for the purpose specified.
2. A game of the character described em-

bodying a pair of identically constructed game pieces adapted to be disposed in spaced confronting relation, each of said pieces embodying a substantially L-shaped body portion indicative of a trench, a plurality of toy men individually pivoted behind the vertical branch of said body portion with their heads projecting above the latter, and a cannon mounted upon each trench and capable of horizontal swinging movement for the purpose specified.

3. A device of the character described embodying a substantially L-shaped member indicative of a trench, a plurality of toy men individually pivoted behind the vertical branch of said body portion with their heads projecting above the latter, a cannon mounted for horizontal swinging movement, and means for detachably supporting the cannon upon the base of the trench.

In testimony whereof I affix my signature.

ALLAN R. MACPHERSON.
